ROLLER ALIGNER

Karl L. Herrmann, South Bend, Ind., assignor to
 The Bantam Ball Bearing Company, South
 Bend, Ind., a corporation of Indiana

Application December 20, 1934, Serial No. 758,355

8 Claims. (Cl. 308—178)

This application is a continuation in part, of my copending application, Serial No. 712,373, filed February 21, 1934, entitled "Thrust bearings" and relates to bearings for use in heavy duty machinery such, for example, as paper calendering machines, rolling mills and other machines having rollers on which a heavy load is exerted.

The principal object of my invention is to provide means which will compensate for deflection or misalignment of a roller, or a plurality of rollers, subjected to heavy loads to thus relieve the bearings therefor from strain and thrust usually imposed thereon.

A further object is to provide an anti-friction member interposed between a bearing supporting a roller subjected to a heavy load such, for example, as a rolling mill roller or calendering machine roller, and a fixed support which will relieve the strain on the bearing due to deflection or end-wise movement of the roller.

Another object is to provide in a machine having a roller subjected to heavy loads, a bearing for the roller and means associated with the bearing which will permit movement thereof relative to its support to relieve any strain imposed thereon due to deflection or end-wise movement of the roller.

Still another object is to provide a bearing which will compensate for the misalignment of a plurality of rollers such as paper calendering rollers, and thus relieve the thrust imposed on the bearing for such rollers when they tend to shift end-wise due to an unleveled setting of the machine.

A further object is to provide a bearing which will permit the several rollers in a vertical stack to rotate freely in their bearings even though the vertical support for such rollers is out of perfect alignment or the longitudinal axes of the rollers are not exactly horizontal or parallel.

Yet another object is to provide in a calender stack a bearing interposed between the bottom roller and one of its supports which will permit of limited longitudinal movement of the roller relative to its support.

Further objects, and objects relating to details of construction and methods of manufacture will be apparent from the detailed description to follow and from the drawings in which,

Fig. 1 is a side elevational view of a calendering machine having my invention incorporated therein.

Fig. 2 is an end elevational view of a calendering machine shown in Fig. 1, looking in the direction of the arrow A.

Fig. 3 is an enlarged sectional view taken on the line 3—3 of Fig. 1, showing the bearing for the bottom calendering machine roller and the bearing aligner interposed between the roller and a support therefor.

Fig. 4 is a sectional view showing the bearing aligner taken on the line 4—4 of Fig. 3, certain of the parts being in full lines to better show the invention.

Fig. 5 is a transverse sectional view taken on the line 5—5 of Fig. 4.

Fig. 6 is an enlarged sectional view taken on the line 6—6 of Fig. 3, showing one of the rollers and the retainer therefor interposed between the calender roller bearing and the support therefor.

Fig. 7 shows the contact or wear plates set in the base and the bearing for the calender roller against which one of the aligning rollers is adapted to contact.

Fig. 8 is a fragmentary longitudinal sectional view showing the drive end of a calender roller taken on the line 8—8 of Fig. 1.

Fig. 9 is an end view of the modified form of bearing aligner, showing the bearing cage and bearing support in section.

Fig. 10 is a plan view of the bearing aligner taken on the line 10—10 of Fig. 9.

Fig. 11 is a detailed sectional view taken on the broken line 11—11 of Fig. 10.

Fig. 12 is an end view of another modified form of bearing aligner showing the bearing cage and bearing support in section.

Fig. 13 is a sectional view looking in the same direction as Fig. 12, taken on the line 13—13 of Fig. 14.

Fig. 14 is a transverse sectional view taken on the line 14—14 of Fig. 12.

Fig. 15 is a diagrammatic sectional view showing the roller of the bearing aligner positioned between wear plates having flat bearing faces.

Fig. 16 is a view similar to Fig. 15, showing wear plates having concave bearing faces.

Fig. 17 is a view similar to Fig. 15, showing wear plates having convex bearing faces.

Fig. 18 is a view similar to Fig. 15 in which an elliptical member is substituted for a roller.

Fig. 19 is a view similar to Fig. 16, including the elliptical member shown in Fig. 18.

Fig. 20 is a view similar to Fig. 17, including the elliptical member shown in Fig. 18.

In heavy duty machinery having rollers subjected to heavy loads or thrusts, considerable difficulty has been experienced in providing bearings for such rollers which will stand up in use because slight misalignment of the rollers or deflections thereof will impose thrust and strain on the bearings, causing them to fail after a short period of time with the result that the expense of maintenance of such equipment is high and the loss of time in making repairs and replacement are considerable. To overcome these objections, I have provided an anti-friction member interposed between at least one of the bearings for the rollers subjected to the heavy load and the support therefor which will permit the bear-

ing to have limited movement relative to the supports, thus compensating for either or both the axial thrust and the radial thrust imposed thereon.

5 In Figs. 1 to 8 inclusive of the drawings, I have shown my invention as incorporated in a paper calendering machine and will first proceed with the description of the invention as relating to that use. In paper calendering machines and 10 other machines in which there are a plurality of horizontal rollers mounted one on top of the other; that is, in a vertical stack, it has been found extremely difficult to set the frame or roller support with such accuracy that the bearings for the 15 rollers will be in true alignment with the journals on the rollers. In such machines there are frequently from nine to thirteen rollers having diameters varying from fourteen inches to thirty-two inches in the stack, the rollers being of a 20 length of three feet to twelve feet, depending on the purpose for which the machine is used.

In such machines the work rollers are supported in radial bearings mounted in raceways formed in the supports and it is extremely difficult 25 to set the supports in perfect alignment so that the raceways are parallel and as the supports are not tied together to prevent one or the other of them from getting out of alignment, the longitudinal axes of the roller bearings are not coincident with the longitudinal axes of the rollers. 30 This will result in heavy loads being put on the bearings which will cause undue wear and early failure due either to deflection of the rollers or slight longitudinal movement thereof.

35 To counteract the forces to which the roller bearings are subjected, I have provided a bearing aligner interposed between the bottom roller and base of the support which will permit a slight end-wise movement of the roller to thus relieve the thrust put on the bearing for the roller, thus 40 permitting normal operation of the same and prolonging the life thereof. If desired, a roller aligner may be used under each bearing at the opposite ends of the bottom roller, or at one end only thereof.

45 While I have heretofore used the term "roller bearing", I have referred to the radial bearing for supporting an end of the calender roller and have not referred to a type or design of bearing as distinguished from a different type such as a ball bearing.

50 Referring to Figs. 1 and 2, I have illustrated a paper calendering machine having side frame members 10 which are slotted at 11 to form raceways to receive the radial bearings 12 for a plurality of work rollers 13. The bottom roller 14 will be more particularly referred to later on in the description. As it is desirable to apply some pressure to the rollers when the paper is run between them, I have shown an adjusting wheel 15 connected by a suitable rod 16 to a lever 17 pivoted at 18 to the frame member 10, there being a screw 19 bearing against the block 20 which bears against the bearing 12 from the top roller 13, the pressure thereon being regulated by the hand-wheel 15. As the adjusting means of the calender roller forms no part of my invention, the same will not be described in further detail.

55 Each of the rollers 13 is, of course, supported in suitable radial bearings 12 carried in the raceway 11 in each of the frame members 10, the bearings being of any suitable design satisfactory for the purpose for which they are used. The bottom roller 14 is reduced at 21 at each end thereof to provide journals mounted in suitable

bearings, one of which is illustrated in Fig. 8. Also, the rollers may be rotated or driven by the pulley B mounted on the extended end of one of the journals 21.

60 Referring particularly to Fig. 8, this bearing comprises an inner race member 22, an outer race member 23 between which are interposed a plurality of rows of rollers 24 each carried in a suitable cage 25. The outer race member 23 is mounted in a cage 26 which is held against longitudinal movement by stop members 27 positioned on opposite sides of the frame member 10 and secured in position by means of the screws 28. The rollers 24 are retained in the bearing against longitudinal movement by the end plates 29 and 15 30. The cage 26 is provided with suitable guides 31 (see Fig. 3) which are adapted to contact with the sides of the raceway 11 on the frame member 10 to properly position the bearing for the roller 14 therein. 20

To permit slight end-wise movement of the roller 14 relative to the frame member 10, I have provided an anti-friction member, before referred to as a bearing aligner, interposed between a bearing for the roller 14 and the support therefor, 25 or at both ends of the roller 14, if desired, which will now be described in detail.

30 A plurality of recesses 32 and 33 are formed respectively in the cage 26 and the upper face of the base of the frame 10 in which are set hardened discs 34 and 35 (see Figs. 6 and 7). Interposed between discs 34 and 35 are rollers 36 which are mounted in slots 37 formed in the retainer 38. An opening 39 is formed in the retainer 38 to receive a pin 40 which extends into an opening 41 formed 35 in the frame member 10. The lower end of the pin is preferably round while the upper end thereof is rectangular and is provided with recesses 42 in the opposed faces thereof. Openings 43 are provided in the retainer 38 into which coil springs 44 are inserted to abut against the recesses 42 in the pin 40, as shown in Figs. 4 and 5, the springs being held under compression by the screws 45. By this construction, the retainer 38 is maintained in a neutral position by the springs 44 but if the 45 same is moved in either direction from its neutral position, it will move against the compression of one or the other of the springs. When the load 50 which has caused the retainer 38 and the rollers 36 to shift from neutral position is removed, the retainer and rollers will return to neutral position, as shown in Fig. 4. It will thus be seen that as an end thrust is applied to the roller 14 to move it in an end-wise direction, the rollers 36 will 55 permit a slight shifting of the roller relative to its end bearing and thus relieve any twisting or pinching of the bearing which would occur without the use of the thrust bearing.

60 My invention finds utility in heavy duty machinery having one or more rollers spaced horizontally and is not confined to rollers mounted in a vertical stack as described in connection with paper calendering machines, it having been found that an equal advantage will be obtained by the use of my invention in connection with rollers 65 which are subject to deflection as well as, or instead of, end-wise movement.

65 In Figs. 9 to 11 inclusive, I have shown a modified form of my invention in which the frame of the machine 50 is provided with a wear plate 51 thereon and the bearing cage 52 is also provided with a wear plate 53 between which the bearing aligner is interposed. As illustrated, I have provided a pair of upstanding supports 54 on the plate 51 attached thereto by the bolts 55 which 70 75

are journaled at 56 to receive outwardly extending bearing members 57 formed on the retainer 58. The retainer 58 is formed with a recess 59 therein to receive the roller 60. As it is desirable to provide the minimum contact between the roller 60 and the retainer 58, I, therefore, provide a plurality of pads or projections 61 thereon which contact only with the roller 60. The bearing members 57 mounted in the journals 56 in the members or plates 54 prevent end-wise movement of the retainer 58 and the roller 60 carried thereby; however, the retainer and roller are permitted to move in a plane substantially parallel with the longitudinal axes of the members 57. I provide a centering means for the retainer 58 which comprises a plurality of pins 62 supported by the supports 54, each having a pointed head 63 engaging in a correspondingly shaped recess 64 formed in the retainer 58. Each of the supports 54 is recessed at 65 and a coiled spring 66 is interposed between the head 63 on the pin 62 and the bottom of the recess 65. I preferably provide one of these centering means on each side of the retainer 58 adjacent to the respective end thereof, as is best illustrated in Fig. 10. It will thus be seen that the bearing for the work roller is permitted to move relative to the support 50 which may be occasioned either by the end-wise movement of the roller causing the bearing 52 to shift there-with or by a deflection of the work roller which would cause a slight tilting of the bearing cage 52 and that in either event the bearing is permitted to move relative to the support, thus compensating for any strain or thrust imposed thereon which it is evident will materially lengthen the life of the bearing.

In Figs. 12 and 14 inclusive, I have illustrated another form of my invention which is very similar to that illustrated in Figs. 9 to 11 inclusive in which I have shown the base 50, the bearing cage 52 and the respective wear plates 51 and 53, as in the previously described construction. In this construction the bearing aligner comprises the cage 70 having a recess 71 therein to receive the rollers 60, the cage being provided with ears 72 extending over the ends of the wear plate 51 to prevent longitudinal movement of the retainer and the rollers relative to its support; that is, the retainer is provided with ears 72 instead of having the bearing members 57 journaled at 56, as shown in the preceding views. In this modification, the centering means comprises bolts 73, each having a nut 74 thereon extending through the upstanding support 75 bolted on the base 50, the upstanding portions being recessed at 76 to receive the coiled spring 77 interposed between the head of the bolt 73 and the bottom of the recess 76, thus maintaining the bearing aligner normally in its neutral position. In this construction I have shown a pair of rollers 60 placed end-to-end in the retainer 70; however, it will be understood that one roller may be employed if so desired but commercially I find it advantageous to use a plurality of rollers, as illustrated.

I preferably provide a plurality of rollers in the bearing aligner so that there will be a minimum amount of friction between the bearing cage and its support in the event the roller having the aligner beneath its bearing is deflected laterally relative to its support because in the twisting or movement of the aligner in that direction, one of the rollers is permitted to roll in one direction and the other roller in the opposite direction. By the use of the plurality of rollers as described, it will thus be seen that the bearing aligner not only

will compensate for longitudinal movement of the work roller but also deflection of the roller in both horizontal and vertical planes so that under any of these conditions the bearing therefor is permitted to move with the work roller journal to maintain an equal thrust on the bearing under any of the working conditions to which the work roller is subjected.

In conventional constructions heretofore mentioned in which the work roller is supported by anti-friction bearings upon deflection of the work roller, the journal in its bearing moves from its true longitudinal axis thus throwing the load on one edge of the bearing. This prevents full distribution of the load on the bearing, thus causing excessive wear on one edge of the race members and the anti-friction members interposed therebetween so that the life of the bearing is relatively short which of necessity requires frequent replacement of parts and loss of the use of the machine while such repairs are being made. The bearing aligner heretofore described permits the bearing for the work roller to tilt or move with the journal so that the load is distributed equally on the bearing in the same manner as though there were no deflection of the work roller.

In Figs. 15 to 20, I have diagrammatically shown different forms of anti-friction members of the bearing aligner positioned between wear plates supported respectively by the bearing cage and machine support. In Fig. 15, I have shown the roller 60 positioned between wear plates 80 and 81 which respectively correspond with the wear plates 34 and 35 and 51 and 53 described in the preceding views. In this form, it will be seen that if the wear plate 80 is shifted longitudinally relative to the wear plate 81 and is also tilted, as previously described, that there will be a slight movement of the bearing and consequently the work roller relative to the support moving the work roller closer to the support due to the fact that the bearing plate 80 will shift from the line F.

For some uses the construction shown in Fig. 15 is to be preferred but in other machines it is desirable to provide a greater contact area between the roller and the wear plates and I have, therefore, shown in Fig. 16 the roller 60 interposed between wear plates 80 and 81 which respectively have concave bearing faces 82 and 83. The amount of curvature of the faces 82 and 83 can, of course, be varied in different sizes and types of machines in accordance with the load imposed on the work roller or depending on the size of the roller 60. The greater area of contact between the roller and wear plates has advantage in some machines in that there is less danger than in the previously described constructions of the roller 60 scoring the wear plates.

In Fig. 17, I have shown a roller 60 interposed between the wear plates 80 and 81 which respectively are provided with convex bearing faces 84 and 85. As stated above in connection with Fig. 16, the curvature of the bearing faces 84 and 85 can be varied for use in machines having different requirements but it will be seen, however, that with this construction the bearing faces 84 and 85 can be so formed that upon tilting of the wear plate 80 relative to the wear plate 81, the same distance can be maintained between the roller and the support as when the roller is in true alignment and has not been subjected to deflection.

In Fig. 18, I have shown a construction similar to Fig. 15 but in which I have substituted an elliptical anti-friction member 86 for the roller 60,

the same being positioned between wear plates 80 and 81 having flat bearing faces. When it is desired to reduce the over-all height of the machine, it is sometimes desirable to substitute the elliptical member 86 for the roller 60 because it will be apparent that this member provides the same bearing surface contact with the wear plates 80 and 81 as would a roller having a diameter indicated by the dotted line C. Thus I am enabled 10 to provide an anti-friction member in the roller aligner which has the same bearing surface contact with the wear plates as the roller C but which will permit bringing the wear plates 80 and 81 much closer together.

15 In Fig. 19, I have shown a construction similar to Fig. 16 but in which I have substituted the elliptical member 86 for the roller 60 and in which I provide for the greater surface contact between the anti-friction member and the wear plates 20 than is possible in the construction shown in Fig. 18 and which has the same advantages as the construction previously described in connection with Fig. 16.

25 In Fig. 20, I have shown a construction similar to Fig. 17 but in which I have also substituted the elliptical member 86 for the roller 60 and which will permit of the several advantages as described in connection with Fig. 17, it being evident that the convex faces 84 and 85 on the wear plates 30 80 and 81 will permit the elliptical member 86 to tilt and also the wear plate 80 to tilt and with it the bearing for the work roller without separating the members 80 and 81, thus maintaining the bearings for the work roller in the same position 35 relative to the frame as though the work roller had not been deflected.

While I have shown several embodiments of my invention, it will be evident that modifications can be made therein without departing from the 40 spirit and substance of my invention, the scope of which is to be measured entirely by the subjoined claims.

What I claim is:

1. In combination with a machine having 45 spaced supports and rollers arranged in a vertical stack carried by said supports, means to permit longitudinal movement of the bottom roller relative to said supports comprising, a thrust bearing interposed between said bottom roller 50 and one of said supports, said bearing having spaced rollers, a retainer therefor having openings extending therethrough, pins extending into said openings secured in said support, and resilient means at opposite sides of each of said 55 pins to permit the rolling of said bearing rollers between said bottom roller and support and to return said bearing rollers to a predetermined position.

2. A thrust bearing to permit longitudinal 60 movement and deflection of a roller and anti-friction bearing therefor relative to their support comprising, an anti-friction member interposed between said roller and support, means to permit rolling of said anti-friction member parallel with 65 the longitudinal axis of said roller, and resilient means to return said anti-friction member to a predetermined position.

3. A thrust bearing to permit longitudinal 70 movement of a roller relative to its support comprising, a radial bearing for said roller, a thrust roller interposed between said radial bearing and support, a retainer for said thrust roller, means

extending from said support into an aperture in said retainer, and means supported by said retainer engaging said first means to normally maintain said roller in a predetermined position, said means permitting said thrust roller to roll parallel with the longitudinal axis of said first roller when longitudinal thrust is applied to the latter.

4. In combination with a machine having spaced supports and a roller subject to deflection, 10 bearings for said roller carried in said support, at least one of said bearings having movement relative to its support, and an anti-friction bearing having free rolling movement between said movable bearing and its support to permit tilting 15 and axial movement of said bearing upon deflection of said roller from its longitudinal axis.

5. In combination with a machine having spaced supports and a work roller subject to deflection and limited end-wise movement, bearings for said roller carried in said support, at least one of said bearings adapted to move out of alignment relative to its support, and an anti-friction bearing comprising a roller positioned transversely of said work roller having free rolling movement between said movable bearing and its support to permit movement of said movable bearing with said work roller upon radial deflection of said roller.

6. In combination with a machine having spaced supports and a plurality of work rollers subject to axial movement and radial deflection, roller bearings for said rollers carried in said supports, at least one of said bearings having movement relative to its support, and means to 35 permit said movable bearing to move with said work roller upon deflection of the work roller supported therein comprising, a roller retainer positioned transversely to said work roller interposed between said movable bearing and its support, a roller in said retainer also positioned transversely to said work roller engaging said 40 movable bearing and its support to permit axial movement of said bearing upon radial deflection of said work roller, and means to return said 45 transverse roller to a predetermined position.

7. In combination with a machine having spaced supports and rollers arranged in a vertical stack carried by said supports, anti-friction bearings for said rollers, means to permit longitudinal 50 movement and deflection from the longitudinal axis of the bottom roller and at least one of the bearings therefor relative to said supports comprising, a thrust bearing interposed between said bottom roller and a support for said one bearing, 55 said thrust bearing having spaced rollers in end-to-end relation, a retainer therefor, and resilient means for permitting the rolling of said bearing rollers between said bottom roller and support and to return said bearing rollers to a predetermined position.

8. In combination with a machine having spaced supports, bearings carried thereby, at least one of said bearings having movement relative to its support, a work roller inserted in said bearings, and a roller interposed between said bearing and support having free rolling movement therebetween whereby said movable bearing will tilt with said work roller upon deflection of said work roller from its longitudinal axis.
